LAWN GUIDE

George P. Wiedman, North Tonawanda, N. Y.

Application January 27, 1949, Serial No. 529

Term of patent 7 years

(Cl. D28—1)

To all whom it may concern:

Be it known that I, George P. Wiedman, a citizen of the United States, residing at North Tonawanda, New York, have invented a new, original, and ornamental Design for a Lawn Guide, of which the following is a specification, reference being had to the accompanying drawings, forming part thereof.

In the drawings:

Fig. 1 is a side elevational view of a lawn guide, showing my new design;

Fig. 2 is an elevational view of the right end as shown in Fig. 1;

Fig. 3 is an elevational view showing the opposite end;

Fig. 4 is a vertical sectional view thereof taken on line 4—4, Fig. 1;

Fig. 5 is a top plan view; and
Fig. 6 is a side perspective view thereof.

I claim:

The ornamental design for a lawn guide, substantially as shown.

GEORGE P. WIEDMAN.
